INVENTOR
George S. Cooke.

ATTORNEY

UNITED STATES PATENT OFFICE

GEORGE S. COOKE, OF ALEXANDRIA BAY, NEW YORK

DISPENSING MACHINE

Application filed August 14, 1929. Serial No. 385,845.

The present invention relates to dispensing machines of the kind disclosed in my United States Patent No. 1,699,608, issued January 22, 1929, and it particularly has for its object to improve the construction 5 of the machine as a whole in the interests of economy of manufacture, to provide an improved top securing means, to mount the operating shaft and rocker members on a single mounting plate securable in position 10 in the machine as a unit, to simplify the lever and link connections between the operating shaft and rocker members, to provide the inclined discharge plate with back stop lugs or ears to insure the articles are discharged 15 from the machine when released, and to provide other features of improvement in the mechanical perfection of the machine which will later appear.

20 In the drawings:

Figure 1 is a perspective view of the invention.

Figure 2 is a cross section on the line 2—2 of Figure 1.

25 Figure 3 is an inverted plan, the base being removed.

Figure 4 is a longitudinal section on the line 4—4 of Figure 2, looking in the direction of the arrow.

30 Figure 5 is a detail perspective view of one of the abutment plates looking at the rear thereof.

In the drawings in which like numerals of reference indicate like parts in all of the figures, 1 designates the base of the device which includes bevelled defining edges and a bottom plate 2 to which the rectangular body shell 3 is secured through the medium of the fixed brackets 4 that are carried by the shell 35 and the securing screws 5 which pass through apertures in the bottom plate 2 and are threaded into sockets in the said brackets, see Figures 2 and 3.

40 The open top of the shell 3 is covered by a plate 6 which is provided with a depending positioning bracket or foot 7 that is adapted to project into the slotted channel brace bar which is secured to the front plate of the 45 shell 3 and serves the additional function of

stiffening that portion of the body shell to which it is attached.

On the back wall of the shell 3 is an apertured lip 9, the back wall not being as rigid as the front wall is able to give slightly so 55 that when a rose bud headed pin 10 which is secured to the top plate 6, is snapped into the aperture of the lip 9 it will interlock therewith and hold the top in place against removal by finger pressure. The back edge 3 of the shell above the location of the apertured lip 9 is provided with a slight depression 3x in which a flat instrument, as a screw driver, may be inserted and by turning the instrument the lid may be prised off. 60

65 The front wall of the shell 3 is provided with a window opening 11 covered by a glass plate 12.

In the shell 3 a straw supporting shelf 13 is mounted in a plane inclined toward the 70 discharge slotway 14 provided at the front of the shell and defined on one side by a drop flange 15 that depends from the front edge of the shelf and on the other or front side by an abutment plate 16 which has drop ears 17 75 constituting an interrupted drop flange that is spaced from and in parallel relation with the flange 15 to form the said slotway. The abutment plate 16 has upstanding ears 18 spaced back from the window to provide the 80 sample display trough, see Figures 2 and 3. At the front the plate 16 has a downwardly bent portion 16x constituting a flat flange, by means of which it is attached to the front wall of the shell in any approved way as for example by welding. The plate 16 also has, at its front edge, upwardly extended ears 16y which lie in a plane parallel to that containing the flange 16x but spaced backwardly 90 therefrom, the ears 16y serving to hold the lower edge of the glass window plate 11. 85

A mounting plate 19 is secured along the underside of the shelf 13 and two transverse spaces 20 are provided in the shelf edge in alignment with similar spaces 21 in the flange 95 15. Two pairs of registering spaces 21 are provided in the drop flanges 16 and 17, the purpose for which will presently appear, see Figures 2, 3 and 4.

A rocker shaft 22 is mounted in bearings 23 100

which, in the present embodiment of the invention, are stamped from the mounting plate 19. At one end the shaft 22 is projected into a sleeve 24 α to which it is pinned, the sleeve 24 α carrying an operating lever 24. A stop pin 25 is secured to the sleeve 24 α within the shell by means of a collar and pin 26 and is adapted to engage stops 27 secured to an end wall of the shell to limit the rocking movement of the shaft 22.

Two U-shaped rocker members 28 are pivoted at 29 to the mounting plate 19. One side arm 30 of each member 28 lies in a plane to pass through the spaces 21 in the drop flanges 15 and 17, while the other arm 31 of each member 28 is stepped at 32 to lie below and across the flanges 15 and 17 when the parts are in the normal or at rest position to prevent falling of straws through the discharge slotway 14, see Figure 3.

Each U-shaped rocker member 28 is flexibly connected by links 33 with a crank plate 34 having spaced ears 36 secured at 35 on the rocker shaft 22. A spring 37 is connected to the pin 26 and to the shelf 13 and serves normally to hold the parts to the position illustrated in Figure 3 of the drawings.

The crank plate 34 also has pairs of ears 36 α between which the links 33 lie and which carry a pin 36 γ on which the links 33 are pivoted. The single crank plate 34 takes the place of four separate cranks 33, 41, 41, 33 of my patented machine (see Figure 3 of Patent No. 1,699,608).

Two bearing ears 38 are stamped from the plate 19 and a U-shaped double bell crank agitator 39 is pivoted on a pin 38 α carried by the ears 38. This agitator includes a pair of upwardly inclined extensions 40 adapted to work up and down through the transverse space 20 in the shelf edge and to engage the straws adjacent the discharge slotway to agitate them and assure against sticking or mis-alignment thereof.

The agitator 39 is linked at 41 between a pair of ears 36 γ to the pin 35 of the crank plate 34 so that when the shaft 22 is rocked the said agitator will be moved as and for the purposes described.

The plate 19, it will thus be seen, carries all of the operating parts of the machine except the operating lever 24 and the return spring 37. The plate 19 and the parts carried thereby may be assembled as a unit before placing the same in the casing. The inclined shelf 13 has ears 17 α stamped from it to which the plate 19 is fastened by screws 19 α , the back edge 19 γ of the plate 19 is bent over to space the plate more nearly horizontally than the shelf.

The operation of the mechanism for delivering the straws in the present machine is essentially the same as that disclosed in my patent referred to and is as follows:

Normally the parts are in the position

illustrated in Figures 1 and 2 of the drawings with the rockable U member arms 31 extending across beneath the drop flanges 15 and 17 and the discharge slotway defined thereby and serving to support the straws against discharge through the said slotway. As the operating lever 24 is forced downwardly the positions of the members 28 will be reversed from that shown in full lines in the said Figure 3 to the positions illustrated in dotted lines in the said figure, or in other words, with the arms 31 withdrawn from across the slotway and the arms 30 inserted through the openings 21 and across the said slotway. The movement of the arms 30 and 31 is such that as the arms 31 are moved from beneath the single straw-to-be-discharged the arms 30 will be moved beneath the remaining straws in the discharge slotway and will support them against discharge movement until the arms 31 assume their normal position above referred to upon release of pressure upon the operating lever 24 and the return action of the parts occasioned by the spring 37.

It will be observed by reference to Figures 2 and 5 of the drawings that the respective arms 31 and 30 operate on planes spaced apart a distance equivalent to the diameter of the straws so that at a certain time in the change of position in the said arms from that illustrated in full lines in Figure 3 to the positions illustrated in dotted lines in that figure, both arms of each member 28 will engage the straw being discharged and as they are moving in opposite directions as diagrammatically illustrated in Figure 5 of the drawings they will impart a partial rotation to the straw by frictional engagement such as will assure against any tendency of the straw to stick and will facilitate the proper discharge thereof from the slotway.

By reason of the provisions of the agitators 39 and 40 and the peculiar cooperation of the arms 30 and 31 in effecting the release of a single straw while supporting the remainder of the straws, and also the provision of the abutment plate 16, all possibility of mis-alignment of the straws with the discharge slotway or of sticking in warm weather is obviated.

As a straw leaves the discharge slotway it falls onto an outwardly downwardly inclined plate 44 carried by the base and onto receiving hooks or fingers 45 which are spaced a considerable distance apart as is clearly illustrated in Figure 1 of the drawings.

The plate 44 is bent to provide a supporting flange 42 by which it is secured to the base 1 with screws 43. It also has back stop lugs or ears 47 stamped from the plate to prevent the straws working back over the high edge of the plate instead of being delivered from the machine.

Of course, the front wall of the shell is

provided with a suitable opening 46 through which the straws may pass.

By spacing the members 45 as shown in Figure 1 of the drawings it is made natural that a person grasping a straw should grasp it intermediately of its ends, thus discouraging unsanitary grasping of the straw at either end. This fact in connection with closure of the shell against the promiscuous handling of the straws renders the device 10 desirably sanitary.

While I have disclosed and described the device as adaptable for use in dispensing soda water straws it should be understood that the invention may be employed for dispensing lead pencils, and matches or any other long thin articles, and by the addition of a suitable coin control means the device 15 may be utilized as a vending machine.

From the foregoing description, taken in 20 connection with the accompanying drawings, it is thought that the novel details of construction, the manner of use and the advantages of my invention will be readily apparent to those skilled in the art to which 25 it relates.

What I claim is:

1. In a dispensing cabinet, a shell section and a base section, said shell section 30 having a discharge slotway adjacent the base section, an article supporting shelf within the shell section, an outwardly and downwardly inclined plate mounted on the base section and projected through the discharge 35 slotway and having catching fingers at the front and upwardly projecting back stop lugs at the rear, and means for discharging articles onto said outwardly and downwardly inclined plate, substantially as shown and described.

2. In dispensing cabinets, a base section, a shell section, means on said base section to receive a discharged article and deliver it to the outside of the shell section, said shell 45 section having a discharge slotway, an article supporting shelf in said shell section inclined to the slotway, a mounting plate secured beneath said shelf, said mounting plate having bearing ears, a rock shaft mounted in 50 said bearing ears, a lever located on the outside of said shell section and connected to said rock shaft to turn the same, a return spring for said rock shaft and stops limiting the throw of said rock shaft, a set of 55 U-shaped rocker members mounted on said carrying plate, an agitator member rockably mounted on said plate, a crank plate secured to said rock shaft and link connections between said U-shaped rocker members, said 60 agitator member and said crank plate, said mounting plate, said U-shaped rocker members, said agitator member, said rock shaft, said crank plate and said link connections being assembled as a unit for mounting in 65 said shell section, substantially as specified.

3. In dispensing devices of the type wherein is provided a cabinet having an inclined article supporting shelf and a discharge slotway; a unit comprising a mounting plate, a set of U-shaped rocker members pivotally mounted on said mounting plate, an agitator member also pivotally mounted on said mounting plate, a rock shaft journaled in bearings on said mounting plate, a crank plate carried by said rock shaft, and links connecting said crank plate with each said U-shaped rocker members and said agitator member, substantially as specified.

4. In dispensing devices of the character described, an abutment plate comprising a body having one edge slit, alternate portions between slits being bent upwardly and the remaining portions being bent downwardly to lie in substantially the same plane normal to the body of the plate, the other edge of 80 the plate being bent downwardly and slotted to provide a pair of upstanding ears which lie in a plane parallel to but not coincident with the downwardly bent portion of said other edge, substantially as and for the purposes specified.

GEORGE S. COOKE.
